LONGUEMARE FRÈRES, OF PARIS, FRANCE.

CARBURETER.

1,175,536.

Specification of Letters Patent. Patented Mar. 14, 1916.

Application filed October 11, 1911. Serial No. 654,106.

To all whom it may concern:

Be it known that I, Georges Longuemare, citizen of the French Republic, residing at 12 Rue du Boissons-St. Louis, Paris, in the 5 Republic of France, have invented certain new and useful improvements in Carbureters, of which the following is a specification.

In the greater number of carbureters 10 when the throttle valve is opened suddenly after the engine has been idling for a certain length of time, hesitation in the running of the motor is almost always experienced. It frequently happens that in order to obtain suitable running when idling the carbureter is regulated with an excess of fuel. In this case condensations of liquid 15 take place in the piping and when the throttle valve is suddenly opened this deposit is carried along in such a manner that the motor is choked by an excess of fuel. If on the other hand the running of the motor when idling is regulated with a mixture suitably proportioned when the valve is opened the 20 partial vacuum in the motor is still too small and the inertia of the liquid opposes its rapid flow; owing to its elasticity the air flows in and the mixture is rendered poor in fuel; this produces a hesitation in the running 25 of the motor in that it is retarded owing to want of fuel. In order to avoid this hesitation in running or picking up it is necessary that the supply from the fuel distributor should, at the precise moment 30 the valve is opened and at this moment only, be suddenly increased in order to compensate for the small vacuum and to enable the mixture to retain the proper proportions of fuel and air. The running of the motor 35 might thus normally be accelerated. At high speed the supply from the distributor should experience a certain resistance in order to prevent an excess of fuel. The present invention permits of obtaining all these 40 desiderata by the employment of a device by which the supply of fuel may be varied or controlled automatically at the moment of opening the valve while the device is rendered inoperative immediately the motor attains 45 its normal running speed.

The accompanying drawing which is given by way of example illustrates a carbureter embodying the invention in vertical section. In this carbureter the fuel distributor or main spraying nozzle is consti-

tuted by a tubular block 2 fitted to the bottom of the main body 3 of the carbureter and provided or formed at its upper part with a frusto-conical head 1 upon which a cap 4 is screwed. Between this cap and the upper extremity of the tubular block 2 a chamber 5 is formed inside the head 1; oblique radial conduits 6 communicate with this chamber; these conduits are formed in the wall of the said head and the external 55 orifice of each of them opens into a circular groove 7 formed at the extremity of this same head serving as a seat for the cap 4. Below its flange the cap is provided with a shoulder so that between the said flange and the extremity of the head a groove of considerable depth can be formed, the jets of fuel spreading radially in this groove upon issuing from the conduits or spraying orifices 6. This groove is opposite the restriction formed by a bifurcato-conical ring or choke-tube 28 arranged in the socket 8 in which the explosive mixture is formed during normal running of the engine.

The cap 4 is traversed vertically and centrally by a tube 9 which with a certain amount of annular clearance 2' enters the tubular block 2 so that its lower part terminates in the supply passage 10 for the fuel which places the said tubular block 2 in communication with the constant level or float vessel 11. At its upper end the tube 9 opens beneath the plug 12 of the throttle valve by means of which the admission of the explosive mixture to the motor is regulated, and the orifice at said upper end of tube 9 constitutes an auxiliary spraying orifice which is brought into operation when the engine is idling. At the middle of its lower segment this plug is provided with a hole 13 registering with the tube 9 and at its upper segment with a recess 14. This same tube 9 passes freely through the bottom of a small cup 15 arranged immediately beneath the plug and at the middle of the socket 8 and of a small bar 16 passing through the said socket transversely. By this arrangement an annular space 17 is formed in the bottom of the cup 15 for facilitating the operation of the carbureter when the engine is idling as hereinafter explained.

The cup 15 communicates with the interior of the socket 8 by means of a hole 18 the free cross section of which can be regu-

lated by means of a pin valve 19. The supply passage 10 terminates at the middle of the constant level vessel or fuel chamber 11 beneath the lower extremity of a hollow 5 column or compensating chamber 20 having perforations 21, 22 placing the interior of the said vessel 11 in communication with the said passage and controlled by a pin valve 23 arranged longitudinally in this column 10 and adapted to be operated above the cover 24 closing the vessel 11. At its lower extremity the column 20 is screwed into the bottom of the vessel 11 and is provided with a shoulder at its upper part in such a manner 15 as to form a head enabling the cover 24 to fit the edge of the vessel 11 with a good joint without the necessity of employing other screws for this purpose. The vessel 11 is vented to atmosphere in any suitable 20 manner, for example, by a hole 24 drilled into the cover horizontally and then downwardly, to prevent the entrance of dust and dirt. The internal space of the hollow column 20 communicates with the atmosphere 25 through holes 25 formed in its head beneath a plug 26 guiding the rod of the pin valve 23 and also communicates with the passage 10 by means of conduits 27.

The arrangement which has just been described has been specially devised with a view to permitting of the perfect operation of the carburetor during idling, on picking up and during normal running of the engine.

35 *Idling.*—The plug 12 of the valve being closed the vacuum existing in the admission conduit can only have effect upon the small free section existing owing to the recess 14 and the hole 13. As in this position of the 40 valve the hole 12 communicates directly with the cup 15 into which the idling tube 9 opens it follows that the section of the fuel takes place through this tube into the passage 10 itself which is supplied from the 45 vessel 11. Now at this period of idling a certain quantity of the liquid which enters the passage 10 passes through the conduits 27 into the hollow column or chamber 20 and a level is established in this column 50 which balances the partial vacuum in the said passage 10. Owing to the particular arrangement of the hollow column 20 (the charge of liquid that it contains adding itself to that in the vessel 11) and also to the 55 reduction of the section of the tube 9 relatively to that of the main distributor the fuel encounters but slight resistance to its ascent in the cup 15 from which it is withdrawn and carried along by the air which is 60 sucked up and passes through the annular space 17 and through the conduit 18 controlled by the pin valve 19. The latter permits of adjusting accurately and to a given predetermined value the precise proportions 65 of air and fuel entering into the composition

of the explosive mixture during the idling of the engine.

Picking up.—During idling the column of liquid around the tube 9 in the block 2 and in the chamber 5 remains constant owing to the arrangement of the valve and to the special admission of air to the auxiliary idling tube, as the flow of air past the orifices 6 is insufficient to draw the liquid through these orifices. The level of this liquid reaching almost to the upper orifice of the oblique passages 6, it follows that when the valve 12 is opened the partial vacuum which then makes itself felt in the socket 8 although very small creates in the choke tube 28 a suction of air which acts upon both the fuel in the chamber 5 and upon the fuel in the tube 9. At this moment of picking up the fuel is drawn from both the float chamber 11 and the chamber 20, and the latter 85 thus constitutes a momentary enriching device, called into operation when the throttle valve is suddenly opened, to provide an increased supply of fuel at this time.

Normal running.—As soon as the quantity of liquid fuel contained in the column 20 at the time of picking up has been exhausted the air which enters this column through the holes 25 passes through the conduits 27 and is carried along by the quantity of liquid supplied by the pin valve 23 and coming from the vessel 11. A kind of emulsion is then produced in the passage 10 as far as the spraying orifices which creates a certain resistance to the supply from the said atomizer. This emulsion increases proportionately with the vacuum in such a manner that an automatic damping of the supply of liquid takes place during normal running of the motor, when this supply would tend to 105 be larger than is desired. Consequently, owing to its special arrangements this carburetor provides a long sought solution to the problem of perfect regulation of the proportions of air and fuel in the formation 110 of the explosive mixture during idling, picking up and normal running of the motor.

When picking-up and during normal full power running, the tube 9 adds its discharge to that of the oblique conduits 6, though to a 115 smaller extent since the mouth of the tube is in a region of less depression than the conical head 1, which is located at the point where the greatest depression occurs. Part of the emulsion formed in the channel 10 120 passes up through the tube 9, but the greater part passes up through the annular space 2' and out through the oblique conduits 6.

The size or number of the holes 25 in the column 20 is important since the area of 125 these holes bears a definite relation to the size of the conduits 27 in order that the correct quantity of air may be introduced into the channel 10. If the holes 25 are too large, too much air is introduced and stratification 130

will result instead of emulsification, whereas if too little air is introduced, the flow of fuel through channel 10 will be unduly augmented.

5. What I claim and desire to secure by Letters Patent of the United States is:—

1. In a carbureter, in combination, a source of fuel supply, a calibrated orifice for measuring the supply of fuel from said source, a calibrated spraying orifice arranged in series with said measuring orifice, a calibrated auxiliary air orifice for admitting air into a considerable vacuum between said fuel orifices to control the feed pressure head through the measuring orifice and to assist the vaporization and spraying of the fuel, and an auxiliary idling spraying orifice distinct from the main spraying orifice also arranged in series with said measuring orifice.

2. In a carbureter, in combination, a source of fuel supply, a calibrated orifice for measuring the supply of fuel from said source, a calibrated spraying orifice arranged in series with said measuring orifice, a calibrated auxiliary air orifice for admitting air into a considerable vacuum between said fuel orifices to control the feed pressure head through the measuring orifice and to assist the vaporization and spraying of the fuel, a throttle valve, and an auxiliary idling spraying orifice distinct from the main spraying orifice also arranged in series with said measuring orifice, the operation of said auxiliary orifice being controlled entirely by the position of the throttle valve.

3. In a carbureter, in combination, a source of fuel supply, a calibrated orifice for measuring the supply of fuel from said source, a calibrated spraying orifice arranged in series with said measuring orifice, a calibrated auxiliary air orifice for admitting air into a considerable vacuum between said fuel orifices to control the feed pressure head through the measuring orifice and to assist the vaporization and spraying of the fuel, and an auxiliary idling spraying orifice distinct from but concentric with the main spraying orifice also arranged in series with said measuring orifice.

4. In a carbureter, in combination, a source of fuel supply, a calibrated orifice for measuring the supply of fuel from said source, a calibrated spraying orifice arranged in series with said measuring orifice, and a momentary enriching device comprising an auxiliary fuel reservoir, acting to momentarily supply fuel between said orifices when suddenly changing from idling to normal running, said device including a calibrated orifice operable during normal running to admit air into a considerable vacuum between said fuel orifices to control the feed pressure head through the

measuring orifice and to assist the vaporization and spraying of the fuel.

5. In a carbureter, in combination, a source of fuel supply, a calibrated orifice for measuring the supply of fuel from said source, a calibrated spraying orifice arranged in series with said measuring orifice, and a momentary enriching device comprising an auxiliary fuel reservoir, acting to momentarily supply fuel between said orifices when suddenly changing from idling to normal running, said device including a calibrated orifice operable during normal running to admit air into a considerable vacuum between said fuel orifices so to control the feed pressure head through the measuring orifice and to assist the vaporization and spraying of the fuel, all of said orifices as well as the main air inlet being of fixed area after initial adjustment.

6. In a carbureter, in combination, a source of fuel supply, a calibrated orifice for measuring the supply of fuel from said source, a calibrated spraying orifice arranged in series with said measuring orifice, a calibrated auxiliary air orifice for admitting air into a considerable vacuum between said fuel orifices to control the feed pressure head through the measuring orifice and to assist the vaporization and spraying of the fuel, and a momentary enriching device comprising an auxiliary fuel reservoir, acting to momentarily supply fuel between said measuring and spraying orifices when suddenly changing from idling to normal running.

7. In a carbureter, in combination, a source of fuel supply, a calibrated orifice for measuring the supply of fuel from said source, a calibrated spraying orifice arranged in series with said measuring orifice, a calibrated auxiliary air orifice for admitting air into a considerable vacuum between said fuel orifices to control the feed pressure head through the measuring orifice and to assist the vaporization and spraying of the fuel, an auxiliary idling spraying orifice distinct from the main spraying orifice also arranged in series with said measuring orifice, and a momentary enriching device comprising an auxiliary fuel reservoir, acting to momentarily supply fuel between said measuring and spraying orifices when suddenly changing from idling to normal running.

8. In a carbureter, in combination, a source of fuel supply, a calibrated orifice for measuring the supply of fuel from said source, a calibrated spraying orifice arranged in series with said measuring orifice, a calibrated auxiliary air orifice for admitting air into a considerable vacuum between said fuel orifices to control the feed pressure head through the measuring orifice and to assist the vaporization and spraying of the fuel,

- an auxiliary idling spraying orifice distinct from the main spraying orifice also arranged in series with said measuring orifice, a throttle valve, and a momentary enriching device 5 comprising an auxiliary fuel reservoir, acting to momentarily supply fuel between said measuring and spraying orifices when suddenly changing from idling to normal running position of the throttle valve, the operation of said auxiliary orifice being controlled entirely by the position of the throttle valve.
9. In a carbureter, in combination, a source of fuel supply, a calibrated orifice 15 for measuring the supply of fuel from said source, a calibrated spraying orifice, a channel connecting said orifices in series, an auxiliary fuel supply chamber connected to atmosphere at its upper end, and a calibrated orifice between said channel and said chamber, the latter receiving fuel from said channel during idling and acting to supply fuel to said channel when suddenly changing from idling to normal running, and said 20 orifice between the channel and chamber acting during normal running to admit air into a considerable vacuum in said channel to control the feed pressure head through said measuring orifice and to assist the vaporization 25 and spraying of the fuel.
10. In a carbureter, in combination, a source of fuel supply, a calibrated orifice for measuring the supply of fuel from said source, a calibrated spraying orifice, a channel 30 connecting said orifices in series, an auxiliary fuel supply chamber connected to atmosphere at its upper end, a calibrated orifice between said channel and said chamber, the latter receiving fuel from said channel 35 during idling and acting to supply fuel to said channel when suddenly changing from idling to normal running, and said orifice between the channel and chamber, acting during normal running to admit air into 40 a considerable vacuum in said channel to control the feed pressure head through said measuring orifice and to assist the vaporization and spraying of the fuel, and an auxiliary idling spraying orifice distinct from 45 the main spraying orifice also connected with said channel.
11. In a carbureter, in combination, a throttle valve, a source of fuel supply, a calibrated orifice for measuring the supply 50 of fuel from said source, a calibrated spraying orifice, a channel connecting said orifices in series, an auxiliary fuel supply chamber connected to atmosphere at its upper end, a calibrated orifice between said channel and 55 said chamber, the latter receiving fuel from said channel during idling and acting to supply fuel to said channel when suddenly changing from idling to normal running position of the throttle valve, and said orifice between the channel and chamber acting 60 during normal running to admit air into a considerable vacuum in said channel to control the feed pressure head through said measuring orifice and to assist the vaporization and spraying of the fuel, and an auxiliary idling spraying orifice distinct from the main spraying orifice also connected with said channel, the operation of said auxiliary orifice being controlled entirely by the position of the throttle valve.
12. In a carbureter, in combination, a source of fuel supply, a calibrated orifice for measuring the supply of fuel from said source, a calibrated spraying orifice arranged in series with said measuring orifice, a calibrated auxiliary air orifice for admitting air into a considerable vacuum between said fuel orifices to control the feed pressure head through the measuring orifice and to assist the vaporization and spraying of the fuel, a throttle valve and an auxiliary idling spraying orifice distinct from the main spraying orifice also arranged in series with said measuring orifice, the fuel discharge into the main body of air from both the spraying orifice and the auxiliary idling orifice being below the throttle valve and unaffected by the pressure beyond said valve.
13. In a carbureter, in combination, a source of fuel supply, a calibrated orifice for 95 measuring the supply of fuel from said source, a calibrated spraying orifice arranged in series with said measuring orifice, a calibrated auxiliary air orifice for admitting air into a considerable vacuum between 100 said fuel orifices to control the feed pressure head through the measuring orifice and to assist the vaporization and spraying of the fuel, a throttle valve, and an auxiliary idling spraying orifice distinct from the main 105 spraying orifice also arranged in series with said measuring orifice, the fuel discharge into the main body of air from both the spraying orifice and the auxiliary idling orifice being below the throttle valve and unaffected by the pressure beyond said valve, and the operation of said auxiliary orifice being controlled entirely by the position of the throttle valve.
14. In a carbureter, in combination, a 115 source of fuel supply, a calibrated orifice for measuring the supply of fuel from said source, a calibrated spraying orifice arranged in series with said measuring orifice, a calibrated auxiliary air orifice for admitting air into a considerable vacuum between 120 said fuel orifices to control the feed pressure head through the measuring orifice and to assist the vaporization and spraying of the fuel, a throttle valve and an auxiliary idling 125 spraying orifice distinct from the main spraying orifice also arranged in series with said measuring orifice, the fuel discharge

into the main body of air from both the spraying orifice and the auxiliary idling orifice being below the throttle valve and unaffected by the pressure beyond said valve, 5 and the said auxiliary idling orifice being located above the level of the fuel in said source and above the main spraying orifice.

15. In a carbureter, in combination, a source of fuel supply, a calibrated orifice for 10 measuring the supply of fuel from said source, a calibrated spraying orifice arranged in series with said measuring orifice, a calibrated auxiliary air orifice for admitting air into a considerable vacuum between 15 said fuel orifices to control the feed pressure head through the measuring orifice and to assist the vaporization and spraying of the fuel, and an auxiliary idling spraying orifice distinct from the main spraying orifice also 20 arranged in series with said measuring orifice, the said auxiliary idling orifice being located above the level of the fuel in said source and above the main spraying orifice.

16. In a carbureter, in combination, a source of fuel supply, a calibrated orifice for 25 measuring the supply of fuel from said source, a calibrated spraying orifice arranged in series with said measuring orifice, a calibrated auxiliary air orifice for admitting air into a considerable vacuum between 30 said fuel orifices to control the feed pressure head through the measuring orifice and to assist the vaporization and spraying of the fuel, a throttle valve and an auxiliary 35 idling spraying orifice distinct from the main spraying orifice also arranged in series with said measuring orifice, the said auxiliary idling orifice being located above the level of the fuel in said source and above 40 the main spraying orifice, and the operation of said auxiliary orifice being controlled entirely by the position of the throttle valve.

17. In a carbureter, in combination, a source of fuel supply, a calibrated orifice for 45 measuring the supply of fuel from said source, a calibrated spraying orifice, an auxiliary idling spraying orifice separated from the main spraying orifice, a momentary enriching device comprising an auxiliary fuel 50 reservoir, acting to momentarily supply fuel between said measuring and spraying orifices when suddenly changing from idling to normal running, and a common fuel passage of large area connecting the measuring 55 orifice, the main and auxiliary spraying orifices and the enriching device.

18. In a carbureter, in combination, a source of fuel supply, a calibrated spraying orifice, an auxiliary main spraying orifice, a 60 separate from the main spraying orifice, a momentary enriching device comprising an auxiliary fuel reservoir, acting to momentarily supply fuel between said measuring and spraying orifices when suddenly chang-

ing from idling to normal running, and a 65 common fuel passage of large area communicating with said source and supplying the main and auxiliary spraying orifices and the enriching device.

19. In a carbureter, in combination, a 70 source of fuel supply, a calibrated orifice for measuring the supply of fuel from said source, a calibrated spraying orifice, an auxiliary idling spraying orifice separate from the main spraying orifice, a momentary enriching device comprising an auxiliary fuel reservoir, acting to momentarily supply fuel between 75 said measuring and spraying orifices when suddenly changing from idling to normal running, and a common fuel passage of large area connecting the measuring orifice, the main and auxiliary spraying orifices, and the enriching device, the said auxiliary idling orifice being located above the level of the fuel in said source and above 80 the main spraying orifice.

20. In a carbureter, in combination, a source of fuel supply, a calibrated orifice for 85 measuring the supply of fuel from said source, a calibrated spraying orifice, an auxiliary idling spraying orifice separate from the main spraying orifice, a throttle valve, a momentary enriching device comprising an auxiliary fuel reservoir, acting to 90 momentarily supply fuel between said measuring and spraying orifices when suddenly changing from idling to normal running position of the throttle valve, and a common fuel passage of large area connecting the measuring orifice, the main and auxiliary spraying orifices, and the enriching device, the fuel discharge into the main body of air from both the spraying orifice and the auxiliary idling orifice being below 95 the throttle valve and unaffected by the pressure beyond said valve.

21. In a carbureter, in combination, a source of fuel supply, a calibrated orifice for 100 measuring the supply of fuel from said source, a calibrated spraying orifice arranged in series with said measuring orifice, a throttle valve, a momentary enriching device comprising an auxiliary fuel reservoir 105 acting to momentarily supply fuel between said orifices when suddenly changing from idling to normal running position of the throttle valve, said device including a calibrated orifice, operable during normal running to admit air into a considerable vacuum 110 between said fuel orifices to control the feed pressure head through the measuring orifice and to assist the vaporization and spraying of the fuel, and an auxiliary idling spraying orifice distinct from the main spraying orifice and mechanically brought into action 115 by the throttle valve only, the fuel discharge into the main body of air from both the spraying orifice and the auxiliary idling 120

- orifice being below the throttle valve and unaffected by the pressure beyond said valve, and the said auxiliary idling orifice being located above the level of the fuel in said 5 source and above the main spraying orifice.
22. In a carbureter, in combination, a source of fuel supply, a calibrated orifice for measuring the supply of fuel from said source, a calibrated spraying orifice arranged in series with said measuring orifice, a throttle valve, a momentary enriching device comprising an auxiliary fuel reservoir acting to momentarily supply fuel between said orifices when suddenly changing from 10 idling to normal running position of the throttle valve, said device including a calibrated orifice, operable during normal running to admit air into a considerable vacuum between said fuel orifices to control the feed 15 pressure head through the measuring orifices and to assist the vaporization and spraying of the fuel, an auxiliary idling spraying orifice distinct from the main spraying orifice and mechanically brought into action 20 by the throttle valve only, the fuel discharge into the main body of air from both the spraying orifice and the auxiliary idling orifice being below the throttle and unaffected by the pressure beyond said valve, and the 25 auxiliary idling orifice being located above the level of the fuel in said source and above the main spraying orifice, and a common fuel passage of large area connecting the measuring orifice, the main and auxiliary 30 spraying orifices and the enriching device.
23. In a carbureter, in combination, a source of fuel supply, a calibrated orifice for measuring the supply of fuel from said source, a calibrated spraying orifice arranged in series with said measuring orifice, a throttle valve, a momentary enriching device comprising an auxiliary fuel reservoir acting to momentarily supply fuel between said orifices when suddenly changing from 35 idling to normal running position of the throttle valve, said device including a calibrated orifice, operable during normal running to admit air into a considerable vacuum between said fuel orifices to control the feed 40 pressure head through the measuring orifice and to assist the vaporization and spraying of the fuel, an auxiliary idling spraying orifice distinct from the main spraying orifice and mechanically brought into action 45 by the throttle valve only, the fuel discharge into the main body of air from both the spraying orifice and the auxiliary idling orifice being below the throttle valve and unaffected by the pressure beyond said valve, and the 50 auxiliary idling orifice being located above the level of the fuel in said source and above the main spraying orifice, and a common fuel passage of large area connecting the measuring orifice, the main and auxiliary 55 spraying orifices and the enriching device.
24. In a carbureter, in combination, a source of fuel supply, a calibrated orifice for measuring the supply of fuel from said source, a calibrated spraying orifice arranged in series with said measuring orifice, a calibrated auxiliary air orifice for admitting air into a considerable vacuum between 60 said fuel orifices to control the feed pressure head through the measuring orifice and to assist the vaporization and spraying of the fuel, all of said orifices as well as the main air inlet being of fixed area after initial adjustment, and an auxiliary idling spraying orifice distinct from the main spraying orifice also arranged in series with said 65 measuring orifice.
25. In a carbureter, in combination, a source of fuel supply, a calibrated orifice for measuring the supply of fuel from said source, a calibrated spraying orifice, a channel connecting said orifices in series, an additional calibrated orifice communicating 70 with said channel between said fuel orifices, and means for producing sub-atmospheric pressure in said channel, the fuel traveling upwardly through said additional orifice when gravity becomes predominant over 75 said pressure and traveling downwardly through said orifice when the sub-atmospheric pressure becomes predominant over 80 gravity.
26. In a carbureter, a source of fuel supply, a distributing nozzle, a connecting channel between said source of supply and said nozzle, and a chamber communicating with said connecting channel through a calibrated orifice located at a calibrated distance from said nozzle, said source of supply communicating with said connecting channel through a regulable orifice located 85 adjacent the orifice which connects the channel and the chamber.
27. In a carbureter, a source of fuel supply, a distributing nozzle, a connecting channel between said source of supply and said nozzle, said source of supply communicating with said channel through a calibrated orifice, and a chamber communicating with said channel through a calibrated orifice, the outlet area of said nozzle being less than the cross-sectional area of the connecting channel, but greater than the combined 90 areas of the said orifices.
28. In a carbureter, a source of fuel supply, a distributing nozzle, a connecting channel between said source of supply and said nozzle, said source of supply communicating with said channel through a regulable orifice, and a chamber communicating with said channel through a calibrated ori- 95

- 120
- 125

face, the outlet area of said nozzle being less than the cross-sectional area of the connecting channel, but greater than the combined areas of the said orifices.

5. 29. In a carburetor, a source of fuel supply, a distributing nozzle, a connecting channel between said source of supply and said nozzle, said source of supply, connecting channel and channel through a calibrated orifice and a chamber communicating with the atmosphere and with said channel through calibrated orifices, the outlet area of said nozzle being less than the cross-sectional area of the connecting channel, but greater than the combined areas of the calibrated orifices leading from the chamber and the source of fuel supply into said channel.

30. In a carburetor, the combination of a source of fuel supply, a distributing nozzle, a connecting channel between said fuel supply and said nozzle, an auxiliary chamber, constituted by a hollow column, an orifice at the upper part of the said column for placing the latter in communication with the atmosphere, a calibrated orifice in the lower part of the said column for establishing communication between the latter and said channel for allowing of the introduction of fuel or air into the said channel according to the running speed of the motor, and means for controlling the cross-section of the said channel.

31. In a carburetor, the combination of a fuel supply chamber, a distributing nozzle, a connecting channel between said fuel supply and said nozzle, a hollow column located in the fuel supply chamber and closed at its upper part, an orifice in the upper part of the said column for placing the latter in communication with the atmosphere, a calibrated orifice at the lower part of the said column for establishing communication between the latter and said channel for allowing of the introduction of fuel or air into the said channel according to the running speed of the motor, and a regulating spindle in the interior of the said chamber for controlling the cross-section of the said channel.

32. In a carburetor, the combination of a fuel supply chamber, a distributing nozzle, a connecting channel between said fuel supply and said nozzle, a hollow column located in the fuel supply chamber and closed at its upper part, an orifice in the upper part of the said column for placing the latter in communication with the atmosphere, a calibrated orifice in the lower part of the said column for establishing communication between the latter and said channel for allowing of the introduction of fuel or air into the said channel according to the running speed of the motor, cross ducts in the interior of the said column for establishing communication between the fuel supply chamber and the said channel, a regulating valve in the interior of the said column for establishing the cross-section of the said channel, a regulating spindle in the interior of the said chamber for controlling the cross-section of the said channel, a main distributing nozzle and an auxiliary nozzle, the both communicating directly with the said channel, and a regulating valve for placing the main nozzle out of operation when the motor is idling.

33. In a carburetor, the combination of a fuel supply chamber, a channel connected therewith, a vertical hollow column located in said fuel supply chamber and closed at its upper part, an orifice in the upper part of the said column for placing the latter in communication with the atmosphere, a calibrated orifice in the lower part of the said column for establishing communication between the latter and the said chamber for allowing of the introduction of fuel or air into the said channel according to the running speed of the motor, cross ducts in the lower part of the said column for establishing communication between the fuel supply chamber and the said channel, a regulating spindle in the interior of the said chamber for controlling the cross-section of the said channel.

34. In a carburetor, the combination of a fuel supply chamber, a channel connected therewith, a hollow vertical column located in said chamber and closed at its upper part, an orifice in the upper part of the said column for placing the latter in communication with the atmosphere, a calibrated orifice in the lower part of the said column for establishing communication between the latter and the said chamber for controlling the cross-section of the said channel, a main distributing nozzle and an auxiliary nozzle both communicating with the said channel, and means for controlling the admission of the fuel automatically at the different running speeds of the motor.

35. In a carburetor, the combination of a fuel supply chamber, a channel connected therewith, a hollow vertical column located in said chamber and closed at its upper part, an orifice in the upper part of the said column for placing the latter in communication with the atmosphere, a calibrated orifice in the lower part of the said column for establishing communication between the latter and said channel for allowing fuel when idling, but allowing air during normal running to pass from the column into said channel, cross ducts in the lower part of the said column for establishing communication between the fuel supply chamber and the said channel, a regulating spindle in the interior of the said column for establishing the cross-section of the said channel, a main distributing nozzle and an auxiliary nozzle, the both communicating directly with the said channel, and a regulating valve for placing the main nozzle out of operation when the motor is idling.

36. In a carburetor, the combination of a fuel supply chamber, a channel connected therewith, a hollow vertical column located in the said chamber, and closed at its upper part, an orifice in the upper part of the said column for placing the latter in communication with the atmosphere, a calibrated orifice in the lower part of the said column for establishing communication between the latter and said channel for allowing fuel when idling, but allowing air during normal running to pass from the column into said channel, cross ducts in the lower part of the said column for establishing communication be-

tween the fuel supply chamber and the said channel, a regulable spindle in the interior of the said column for controlling the cross-section of the said channel, a main distributing nozzle, comprising a tubular block communicating with the said channel and projecting into the carbureting chamber, a cap surmounting said block, an internal chamber formed in the upper part of the block and closed by the said cap, a series of calibrated oblique passages formed in the block and opening into said internal chamber, a circular groove below the projecting rim of the said cap and upon the upper end of the said block for connecting together the orifices of the said oblique passages, an auxiliary distributing nozzle also communicating with said channel, and a regulating valve for placing the main distributing nozzle out of operation when the motor is idling.

36. In a carbureter, the combination of a fuel supply chamber, a channel connected therewith, a hollow vertical column located in the said chamber and closed at its upper part, an orifice in the upper part of the said column for placing the latter in communication with the atmosphere, a calibrated orifice in the lower part of the said column for establishing communication between the latter and said channel for allowing fuel when idling, but allowing air during normal running to pass from the column into the said channel, cross ducts in the lower part of the said column for establishing communication between the fuel supply chamber and the said channel, a regulable spindle in the interior of the said column for controlling the cross-section of the said channel, a main distributing nozzle, comprising a tubular block communicating with said channel and projecting into the carbureting chamber, a cap surmounting said block, an internal chamber formed in the upper part of the block and closed by the said cap, a series of calibrated oblique passages formed in the block and opening into said internal chamber, a circular groove below the projecting rim of the said cap and upon the upper end of the said block for connecting together the orifices of the said oblique passages, an auxiliary nozzle, comprising a vertical tube arranged in the interior of and concentrically to the block, for communicating with said channel, a regulating valve for placing the main nozzle out of operation when the motor is idling, a passage of reduced section in the said valve, a sleeve in the carbureting chamber surrounding the upper part of the vertical tube and communicating with the reduced passage of the valve during idling of the motor, a duct for allowing air to enter the said sleeve and a regulable spindle for controlling the cross-section of the said duct.

In testimony whereof I affix my signature in presence of two witnesses.

GEORGES LONGUEMARE.

Witnesses:

H. C. COXE,
GEORGES BONNEUIL.

operation when the motor is idling, and a passage of reduced section in the said valve for controlling a separate air inlet for the auxiliary nozzle during said idling.

37. In a carbureter, the combination of a fuel supply chamber, a channel connected therewith, a hollow column located in the said chamber and closed at its upper part, an orifice in the upper part of the said column for placing the latter in communication with the atmosphere, a calibrated orifice in the lower part of the said column for establishing communication between the latter and said channel for allowing fuel when idling, but allowing air during normal running to pass from the column into the said channel, cross ducts in the lower part of the said column for establishing communication between the fuel supply chamber and the said channel, a regulable spindle in the interior of the said column for controlling the cross-section of the said channel, a main distributing nozzle, comprising a tubular block communicating with said channel and projecting into the carbureting chamber, a cap surmounting said block, an internal chamber formed in the upper part of the block and closed by the said cap, a series of calibrated oblique passages formed in the block and opening into said internal chamber, a circular groove below the projecting rim of the said cap and upon the upper end of the said block for connecting together the orifices of the said oblique passages, an auxiliary nozzle, comprising a vertical tube arranged in the interior of and concentrically to the block, for communicating with said channel, a regulating valve for placing the main nozzle out of operation when the motor is idling, a passage of reduced section in the said valve, a sleeve in the carbureting chamber surrounding the upper part of the vertical tube and communicating with the reduced passage of the valve during idling of the motor, a duct for allowing air to enter the said sleeve and a regulable spindle for controlling the cross-section of the said duct.

In testimony whereof I affix my signature in presence of two witnesses.
